FACIAL VAPORIZER

Clifford E. Grube, Niles, Ill., assignor to Associated Mills, Inc., Chicago, Ill.

Filed June 5, 1967, Ser. No. 7,347

Term of patent 14 years

(Cl. D83—1)

FIGURE 4 is a partial rear elevational view thereof, the base portion having the same appearance as the base design shown in FIGURES 2 and 3.

I claim:

The ornamental design for a facial vaporizer, substantially as shown and described.
